UNITED STATES PATENT OFFICE.

ARTHUR L. HAWKESWORTH, OF BUTTE, MONTANA.

DRILL.

1,380,554.

Specification of Letters Patent. Patented June 7, 1921.

Application filed March 21, 1919. Serial No. 283,954.

To all whom it may concern:

Be it known that I, ARTHUR L. HAWKESWORTH, a citizen of the United States, residing at Butte city, in the county of Silver Bow and State of Montana, have invented 5 certain new and useful Improvements in Drills, of which the following is a full, clear, and exact description, reference being had to the accompanying drawings, forming a part hereof.

The present invention is directed to improvements in drills provided with detachable bits or cutters, the object of the invention being to provide means for effectively 15 locking the bit to the shank of the drill and yet permit of its ready removal when the occasion arises to detach the bit for purposes of sharpening the same, or replacing a worn out bit with a new one. The advantages of 20 the improved construction will be fully apparent from the following detailed description in connection with the accompanying drawings in which—

Figure 1 represents an elevation of a drill 25 turned so as to present the wide ends of the central interlocking tongue and groove of the bit and shank respectively; Fig. 2 is a side elevation of the drill; Fig. 3 is an elevation of the bit detached and turned to present 30 the narrow end of its tongue; Fig. 4 is an elevation of the shank turned to present the narrow end of its groove; Fig. 5 is a bottom plan of the bit; and Fig. 6 is an end view of the shank showing in plan the several formations coöperating with the formations on the bottom of the bit.

Referring to the drawings, 1, represents a 35 drill-bar or shank provided with an axial passage-way or duct *a* for the circulation of water usually employed in drilling operations as well understood in the art. The shank terminates at one end (the end opposite that from which the same is operated) in a tapering transverse groove 2 disposed across 40 the axis of the shank, the groove being of uniform depth and being disposed on a diagonal or at an incline to the axis (longitudinal) of the shank. The end faces *h*, *h*, of the shank on either side of the groove are disposed 45 in the same plane, said plane being parallel with the plane of the bottom of the groove. The taper of the side or bounding walls of the groove is in a direction away from the cutting end of the drill for a reason 50 son to presently appear. Leading from the sides of the groove 2 are recesses 3, 3, of

uniform and equal depth, the bottoms of the recesses under the circumstances being necessarily parallel to the converging side walls of the groove from which they lead. 60 The bit 4 is formed or provided with a tongue 5 snugly fitting the groove 2, said tongue being provided with side ribs 6, 6, co-operating with the recesses 3, 3. To attach the bit to the shank, the tongue 5 is inserted 65 with its narrow end into the wide end of the groove 2, the ribs 6, 6, at the same time being received by the recesses 3, 3. By then moving the bit across the shank the full limit or until further movement is arrested 70 by the converging walls of the groove, the bit will be in proper working position. When in position the duct *a'* with which the bit is provided will be in alignment with the duct *a* of the shank so that the water is free 75 to flow to the surface being drilled.

The taper of the groove 2 (and necessarily that of the tongue 5) being away from the cutting end of the drill, it follows that when the bit is once attached and the drill 80 operated, the axial pressure or blows imparted to the shank to carry on the drilling will tend to drive the shank "up" the incline of the top face *t* of the tongue, or what amounts to the same thing, to drive the bit 85 "down" the incline of the bottom of the groove 2, this action having the effect of tightening the bit on the shank instead of loosening the same, the bit being all the time forced toward the narrow end of the 90 groove 2. At the same time the interlocking action between the members 3 and 6 serves to prevent displacement of the bit in the line of the axis of the shank. To detach the bit a slight tap delivered against the same at 95 the narrow end of the groove 2 will force the bit across the shank axis toward the wide end of the groove as indicated by the arrow in Fig. 2, thereby permitting ready withdrawal of the bit. While in the present embodiment of my invention I show the tongue 5 disposed on the bit and the groove 2 and recesses 3 on the shank, it would be fully within the spirit of my invention to reverse the positions of the members, forming the 100 tongue on the shank and the groove with its recesses on the bit. The cross-sections of the groove and recesses may obviously be varied, my invention in no wise restricting me to the forms here shown. In the present 105 embodiment of the invention, when the parts are assembled, the faces of the offsets *e*, *e*, on

either side of the tongue 5 rest against the faces h , h , on either side of the groove 2, the top face t of the tongue bearing against the bottom of the groove. In the form here 5 shown the lateral recesses 3 are disposed in a common plane transverse to the axis of the drill, necessitating a like disposition for the ribs 6; but it is obvious that I am not to be limited to this precise arrangement for 10 these parts. Neither do I wish to be restricted to ribs 6 made continuous as here shown, any equivalents thereof coming within the scope of the invention. The tool may in fact be changed in many particulars without 15 involving a departure from the basic principle of the invention.

Having described my invention what I claim is:

1. In combination with a drill-bar or 20 shank, a bit movable across the shank, tapering transverse groove disposed across the axis of the drill and at an incline to said axis being formed on one of the members, the end faces of the member on either side of the 25 groove being parallel to the bottom of the groove, a corresponding tapering tongue and bounding offsets therefor being formed on the opposite member and interlocking with the formations on the first member, the direction of the taper of the groove and tongue 30 aforesaid relatively to the cutting end of the drill being such as to cause the bit to tighten on the shank during the drilling operation, suitable recesses having parallel side 35 walls leading from the groove aforesaid, and formations on the opposite member engaging said recesses, whereby the bit is positively secured to the shank.

2. In combination with a drill-bar or 40 shank, a bit movable across the axis of the shank, a tapering transverse groove dis-

posed across the axis of the drill and at an incline to said axis being formed on one of the members, the end faces of the member on either side of the groove being parallel to 45 the bottom of the groove, a corresponding tapering tongue and bounding offsets therefor being formed on the opposite member and interlocking with the formation on the first member, the direction of the taper of 50 the tongue and groove aforesaid relatively to the cutting end of the drill being such as to cause the bit to tighten on the shank in the drilling operation, recesses having parallel side walls leading from the sides of the 55 grooves aforesaid, and suitable formations on the tongue for entering said recesses and positively securing the bit to the shank.

3. In combination with a drill-bar or 60 shank, a bit movable across the shank, a transverse groove disposed across the axis of the shank at an incline to said axis and tapering on the sides in a general direction from the cutting end of the drill, lateral recesses having parallel side walls leading 65 from the groove in a direction transverse to the axis of the shank, the faces of the shank terminal on either side of the groove being parallel to the groove bottom, a bit provided with a transverse tongue shaped to 70 be received by, and to engage the walls and bottom of the groove, ribs on the tongue for entering the recesses aforesaid, the tongue being bounded by offsets adapted to engage and be supported by the end faces of the 75 shank on either side of the groove.

In testimony whereof I affix my signature, in presence of two witnesses.

ARTHUR L. HAWKESWORTH.
